United States Patent Office

Des. 204,257
Patented Apr. 5, 1966

204,257

ARMCHAIR

Charles R. Pollock, 373 Henry St., Brooklyn, N.Y.

Filed Dec. 28, 1964, Ser. No. 83,179

Term of patent 14 years

(Cl. D15—1)

FIG. 2.

FIG. 1.

FIG. 3.

FIG. 5.

FIG. 4.

FIG. 1 is a front perspective view of an armchair showing my new design and disclosing one side thereof—the other side being identical therewith;

FIG. 2 is a front perspective view thereof;

FIG. 3 is a rear view thereof;

FIG. 4 is a top view thereof; and

FIG. 5 is a bottom view thereof.

I claim:

The ornamental design for an armchair, as shown and described.
